2 Sheets-Sheet 2

UNITED STATES PATENT OFFICE.

GUSS M. KING, OF FLAT ROCK, NORTH CAROLINA.

AUTOMATIC SAND SIFTER.

Application filed February 14, 1925. Serial No. 9,173.

To all whom it may concern:

Be it known that I, GUSS M. KING, a citizen of the United States, residing at Flat Rock, in the county of Henderson and State of North Carolina, have invented certain new and useful Improvements in Automatic Sand Sifters, of which the following is a specification, reference being had to the accompanying drawings.

10 This invention relates to sifting devices, and particularly to devices for sifting sand.

The general object of the invention is to provide a very simple and readily operated mechanism which is particularly effective in 15 sifting sand for the use of plasterers, brick-layers, tile setters, and foundries, all of which trades require that the sand used shall be of a uniform grade and some fine and some coarse for different kinds of work.

20 A further object is to provide a device of this character in which a shaking screen is used provided with means whereby vibration is given to the screen as it is reciprocated to thereby cause the disintegration of 25 any lumps of sand.

A still further object is to provide means whereby the amplitude of the vibrations given to the screen may be varied or adjusted.

30 Other objects will appear in the course of the following description.

My invention is illustrated in the accompanying drawings, wherein:—

Figure 1 is a top plan view of a screening 35 machine constructed in accordance with my invention;

Figure 2 is a side elevation thereof;

Figure 3 is a longitudinal sectional view through the screening mechanism;

40 Figure 4 is a vertical fragmentary section on the line 4—4 of Figure 2;

Figure 5 is an enlarged fragmentary elevation of the rack 38 and the adjacent end of the screening frame;

45 Figure 6 is a fragmentary section showing another method of connecting the screw 39 to the lever 36.

Referring to these drawings, it will be seen that I have provided a shaking screen 50 which is mounted upon a base. This base may be of any suitable construction but, as illustrated, consists of a supporting frame 10 preferably made with longitudinally extending beams and transversely extending beams 55 or in any other suitable manner. Mounted

upon this base at opposite sides thereof and extending upward therefrom are the supporting springs 11. These may be either flat metal springs, coiled springs or wooden springs such as are used in amalgamators, 60 classifiers and the like. Supported by these springs 11, which springs have relatively enlarged heads 12 and 12^a, is a supporting frame 13 which may be of any suitable construction and either made of iron or 65 wood, this frame 13 being pivotally connected to the head 12^a by a pin, bolt or other like suitable member 14, while the forward end of the frame 13 is connected to the forward most pair of springs 11 by means of a pin 14 70 which extends into a slot 15 formed in the head 12.

It will thus be seen that this frame 13 may be given a longitudinal reciprocating movement and that the springs 11 will yield to 75 permit this movement. This frame 13 supports a downwardly and rearwardly extending chute 16 having side walls 17. This chute and its side walls are preferably made of sheet metal. Mounted upon the frame 13 80 and oscillating therewith is a screen frame 18 carrying the reticulated screen 19. This screen, of course, will have a mesh suitable for the work to be done and the forward end of the screen frame is provided with the outlet spout 20, as shown in Figure 1, which is on a level with the screen 19 so that the tailings or screenings will be discharged into and through this spout, while the sifted material as, for instance, sand will pass down 85 through the screen 19 and onto the pan or chute 16 and be discharged at the rear end of the machine.

The forward end of the screen frame is, of course, provided with a transverse bar 21 90 which prevents the sand or other material from moving forward off the screen, and attached to the screen frame, as by bolts or in any other suitable manner, is the yoke 22 which is preferably made of strap iron and 95 which carries at its forward end the downwardly depending rounded lug or protuberant member 23.

Mounted upon the base 10 in any suitable manner as, for instance, by brackets 24 and 100 uprights 25 is a supporting frame having longitudinally extending members 26 braced from each other in any suitable manner, and passing through these sills or beams is a 105 driving shaft 27 illustrated as having a 110

2

crank 28 at one end whereby it may be operated, though power may be used to operate this shaft, as by means of the belt pulley 29. Mounted upon this shaft is the gear 5 wheel 30 which meshes with a pinion 31 mounted upon a crank shaft 32 supported in suitable bearings in the sills 26, and connected to this crank shaft is the connecting rod or pitman 33, which in turn is connected 10 to a transverse pin 34 carried by the yoke 22. This pitman is preferably provided with oil cups 35 whereby the bearings for the extremities of the pitman are lubricated.

It will be obvious now that a rotation of 15 the shaft 27 will cause a reciprocation of the frame 13 and of the screen 19, but in order to give a jogging motion or vibration to the screen I provide a lever 36 which is pivotally mounted at 37 upon the sill beams 26 or 20 in any other suitable manner, this lever at its forward end carrying a sinuous rack 38 with which the rounded protuberance 23 is adapted to coact. The forward end of this lever 36 is operatively engaged by an adjusting 25 screw 39 carrying a collar 40 bearing against the lever, and this adjusting screw passes through a screw-threaded opening 41 carried upon a transverse bar 42. The upper end of this adjusting screw is provided 30 with a handle whereby it may be manipulated. It will be obvious that the adjusting screw might be fixed from vertical movement and have its screw-threads engaging with a nut on the lever, as illustrated 35 in Figure 6, but the effect of this adjusting screw is to shift the toothed end of the lever up or down as desired. If the toothed end of the lever is shifted upward, then it is obvious that as the screen is moved the protuberant portion 23 which is connected to 40 the yoke 22 will ride over the sinuous corrugations of the rack 38 and this will give a series of vertical jolts or vibrations to the screen frame 13 and thus to the screen itself, thus shaking up the mass of sand upon 45 the screen, breaking it up into finer particles and doing away with the necessity of stirring up this sand in order that it may pass through the screen properly. The degree of shock or jar given to the screen as it moves forward or rearward will be regulated by turning the screw 39. If the screw 39 is turned so that the toothed portion of the rack 38 is lowered, it will be obvious 50 that the amplitude of the vertical vibrations given to the screen will be smaller than when the rack 38 is raised. The vertical movement of the screen is permitted by reason of the slots 15 in the heads 12 and the 55 pivotal connection of the rear end of the screen with the rear springs.

60 It is to be noted from Figure 1 that the screen frame 18 is preferably hinged by hinges 43 to the frame 13. This permits the screen frame and screen to be readily

changed at any time and also permits the screen frame 18 to be thrown upward and over so as to discharge any material which may have caught upon the screen and which has not passed out through the spout 20. 70

This machine in actual practice has been found to be very effective indeed for the purpose of screening sand and, of course, the fineness of the sand screened will depend entirely upon the mesh of the screen 19, and I 75 contemplate that the screens shall be changed according to the work to be done. As the screen is reciprocated, the material will be shaken longitudinally on the screen and at the same time jolted vertically and 80 the tailings or screenings, that is, those portions of the material which will not pass through the screen, will eventually pass out through the discharge spout 20, while the screened sand or other material will pass 85 down through the screen onto the chute 16 and be discharged at the rear end of the machine.

While I have particularly designed this mechanism for the purpose of screening 90 sand, I do not wish to be limited thereto as it is obvious that this motion might be used to secure a reciprocation and vertical vibration of screening and shaking tables such as are used in the treatment of ores. 95 Furthermore, it is obvious that many changes might be made in the details of construction and arrangement of parts without departing from the spirit of the invention as defined in the appended claims. 100

I claim:—

1. A device of the character described comprising a base, a plurality of springs mounted upon the base and extending upward therefrom, a frame mounted upon the upper ends of said springs and having limited vertical movement with relation to the upper ends of the springs, a yoke attached to the forward end of the frame, means connected to said yoke whereby the frame may be reciprocated, and means adjustable into or out of the path of movement of the yoke for giving a vertical vibration to the yoke and the frame. 110

2. A device of the character described comprising a base, a plurality of springs mounted upon the base and extending upward therefrom, a frame mounted upon the upper ends of said springs and having a limited vertical movement with relation to the upper ends of the springs, a yoke attached to the forward end of the frame, means connected to said yoke whereby the frame may be reciprocated, a downwardly protuberant, rounded member mounted upon the extremity of the yoke, a lever pivoted intermediate its ends and extending beneath said yoke, said lever at this end being formed with a sinuous rack over which the downwardly protuberant member is adapt- 125 130

ed to ride as the frame is reciprocated, and means engaging the forward end of said lever whereby the lever may be adjusted.

3. A device of the character described comprising a base, a plurality of springs mounted upon the base and extending upward therefrom, a frame mounted upon the upper ends of said springs and having a limited vertical movement with relation to 10 the upper ends of the springs, a yoke attached to the forward end of the frame, means connected to said yoke whereby the frame may be reciprocated, a downwardly protuberant, rounded member mounted upon 15 the extremity of the yoke, a lever pivoted intermediate its ends and extending beneath said yoke, said lever at this end being formed with a sinuous rack over which the downwardly protuberant member is 20 adapted to ride as the frame is reciprocated, and means engaging the forward end of said lever whereby the lever may be adjusted including an adjusting screw engaging the lever.
- 25 4. A device of the character described comprising a supporting base, springs extending upwardly from the base, a frame operatively supported upon the upper ends of said springs, the attachment of the frame 30 to the springs permitting limited upward movement of the frame, a yoke attached to the forward end of the frame, a driving shaft having a gear wheel thereon, a crank shaft, a pinion engaging said gear wheel 35 and mounted on the crank shaft, a con-

necting rod between the crank shaft and the yoke, means for causing vertical vibrations of the frame comprising a downwardly extending, rounded member mounted upon the yoke, a lever disposed below the yoke and 40 having a sinuous rack mounted thereon with which the downwardly protuberant member is adapted to engage as the frame is reciprocated to thereby cause vertical vibrations of the frame, and an adjusting screw 45 having engagement with the forward end of the lever.

5. A device of the character described comprising a reciprocable frame, means supporting the frame for reciprocation but 50 permitting the frame to have limited vertical movement, a yoke attached to the forward end of the frame, means connected to said yoke whereby the frame may be reciprocated, a downwardly protuberant, 55 rounded member mounted upon the extremity of the yoke, a lever having one end extending beneath said yoke and at this end being formed with a sinuous rack over which the downwardly extending, protuber- 60 ant member is adapted to ride as the frame is reciprocated, and means engaging said lever whereby the lever may be adjusted toward and from the path of movement of the downwardly protuberant, rounded mem- 65 ber.

In testimony whereof I hereunto affix my signature.

GUSS M. KING.
